(57) CLAIM

The ornamental design for a pocket, as shown and described.

DESCRIPTION

FIG. 1 is a front elevational view of decorative stitching for a pocket showing my new design; and, FIG. 2 is a front view thereof, shown in the environment of a pair of pants.

The solid outlines in FIG. 1 and the thick dotted lines in FIG. 2 shown on the surface of the pocket represent stitching and are part of the claimed design. The broken lines shown in FIG. 1 and the thinner broken lines shown in FIG. 2 represent environmental structure only and form no part of the claimed design.

The claimed pocket is not limited to use with pants as is shown in FIG. 2, but may be applied to any article of apparel, accessory, or other personal item, such as, for example and without limitation: pants; shorts; a skirt; a shirt; a blouse; a one-piece article of clothing such as a dress, pajamas, a robe, a sarong, or a romper; a belt; an armband; a wristband; a bracelet; an ankle band; a headband; a scarf; a money belt; a travel wallet; an undergarment; outerwear such as a sweater, a coat, a jacket, a vest, a sweatshirt, a fleece, or a poncho; a hat; a cap; a helmet; a handbag; a purse; an article of luggage such as a suitcase, a duffel, a grocery bag, a tote bag, a backpack, a messenger bag, a laptop bag, or a pannier bag such as for use on a bicycle or motorcycle; a wallet; a makeup bag; a toiletry case; footwear; a sock; a glove; or a bathing suit.

Further, the claimed pocket is not limited to use with wearable items.
